DESIGN FOR A CENTER STRIPED CIGARETTE LIGHTER

Alexander S. Weston, New York, N. Y.

Application May 24, 1943, Serial No. 110,271

Term of patent 14 years

To all whom it may concern:

Be it known that I, Alexander S. Weston, a citizen of the United States, residing at New York, in the county of New York and State of New York, have invented a new, original, and ornamental Design for a Center Striped Cigarette Lighter, of which the following is a specification, reference being had to the accompanying drawing, forming a part thereof.

In the drawing:

Fig. 1 is an elevational view of a center striped cigarette lighter, showing my new design;

Fig. 2 is a top view of the same;
Fig. 3 is a bottom view thereof.

The characterizing features of my design for the cigarette lighter shown reside in the contrasting stripes extending circumferentially about the center of the lighter in combination with the ornamentation on the end faces thereof, all as illustrated.

I claim:

The ornamental design for a center striped cigarette lighter, as shown, and described.

ALEXANDER S. WESTON.
